FOLDING CARD TABLE

William G. Bryant, Sacramento, Calif.

Application November 9, 1955, Serial No. 545,969

1 Claim. (Cl. 311—85)

The invention relates to folding-leg tables and, more particularly, to tables having legs swingable in unison from closed to open and from open to closed position.

Card tables and other game tables used only upon occasions have long utilized folding legs for ease of storage. Most of such tables have awkwardly acting, independently foldable legs; and earlier attempts to construct tables having legs capable of swinging to extended and to folded position in unison have usually involved either sliding or other high friction members or relatively complex systems of cranks and levers.

It is therefore an object of this invention to provide a card table which is simple in construction and which is therefore durable and economical.

It is another object of the invention to provide a card table which enables the user completely to unfold or to fold the table legs in a matter of but one to two seconds.

It is yet another object of the invention to provide a card table which has legs capable of unfolding or extending in unison and whose legs automatically lock in fully extended position.

It is a further object of the invention to provide a table which is sturdy and which does not wobble in use.

It is a still further object of the invention to provide a card table having legs which although securely locked in extended position can be unlocked and swung into folded attitude by a flick of the user's finger.

It is yet another object of the invention to provide a generally improved card table.

Other objects, together with the foregoing, are attained in the embodiment described in the following description and illustrated in the accompanying drawing in which:

Figure 1 is a view of the table from below, the legs being shown in fully folded or retracted position.

Figure 2 is a view along the plane indicated by the line 2—2 of Figure 1 but with the legs in partially extended position.

Figure 3 is a view similar to that of Figure 2 but with the legs in fully extended or projected position.

Figure 4 is a side elevation of the table shown in Figure 3, a portion of the figure being broken away to reduce the extent thereof.

Figure 5 is a shewing to an enlarged scale, of the leg bracing, locking and actuating-linkage members, the table top and linkage members when in folded position being shown in outline.

While the table of my invention is susceptible of numerous embodiments depending upon the environment in which used, a number of the herein shown and described tables have been made and used and have performed in an eminently satisfactory fashion.

The table of my invention preferably includes a top 6, of the picture-frame type having four perimeter members 7 suitably connected at their four junctions to form a square framework. A table cover 8 is secured to the upper side of the top 6 and provides the customary playing or gaming surface. Depending from each of two opposite margins of the top is a short apron 9, and from the other opposite margins a pair of deep aprons 10, serving to stiffen the structure and lending to it a finished appearance.

2

Even greater strength and rigidity is furnished the table by provision of a central bracing member 11 and a pair of parallel stiles 12 traversing the framework of the table top and appropriately secured to the top and to each other, as by halved joints.

The table structure is substantially symmetrical about an axis 13 and, except for variations specifically pointed out, a description of the structure and operation of one of the sides will serve equally to describe the other.

With especial reference, therefore, to the structure shown on the left-hand side of the axis 13, and as shown in Figure 1, it will be seen that a pair of substantially identical table legs 16 is securely mounted, as by mortise and tenon joints, to a cross rail 17 adjacent the ends of the rail. Each of the table legs 16 includes a long main portion 18 and a subsidiary or bracing portion 19, the thickness provided by both portions accommodating an elongated receptacle 21, or channel, carved out of the upper inner portion of each leg, as appears most clearly in Figure 5, and serving to receive or house a pair of toggle members 22, or links, or bracing members, when such members are folded in a fashion later to be described.

The cross rail 17 is pivotally mounted on the top framework, as by hinges 26, and, since both legs 16 are secured to the cross rail 17, both legs swing in unison with the rail as it moves from a retracted position, substantially parallel to the table top, outwardly to an extended position substantially normal to, or at right angles to, the table top.

Serving as a limit stop to the cross rail as it assumes a vertical, fully extended, or normal attitude, is a corner bracket 27 and a corner bracket 28, each mounted on opposite corners of the long apron 10. With especial reference to Figure 5, for example, it can clearly be seen that the cross rail 17, when in vertical attitude, is restrained against swinging outwardly and farther than normal by the short apron 9 and by the corner bracket 28 mounted on the deep apron 10. The vertical dimension of the cross rail 17 is preferably adjusted so that when the cross rail is in vertical attitude the bottom 27 of the rail is substantially co-planar with the bottom surface 28 of the deep apron 10 so as to give a sturdy, continuous, skirt-like aspect to the table regardless of the position from which the table is observed.

Simultaneous motion of the pair of legs 16 is obtained not only by the common mounting of the legs on the cross rail 17 but also by virtue of a cross bar 31 rotatably mounted in brackets 32 secured to the stile 12. The opposite ends 33 and 34 of the cross bar 31 project outwardly beyond the brackets 32, the ends 33 and 34 having securely mounted thereon, in an attitude normal to the axis 36 of the bar, a toggle crank 41 pivotally mounted as by a pin 42, to a toggle link 43, or toggle arm, or bracing arm. The bracing arm 43 is also pivotally mounted to rotate about a pin 44 transversely disposed in and adjacent to the upper end of the channel 21 in the leg 16, as shown in Figure 5, the crank 41 and the arm 43 conjunctively forming the toggle members 22 referred to above.

As appears in outline in Figure 5, when the table top 6 and the table leg 16 are in substantially parallel location, corresponding to folded leg positions, the toggle members 22 are also in folded attitude and are largely retracted into the channel 21 in the leg 16 so as to permit full leg folding.

When, however, the leg 16 is swung outwardly, to extended attitude the toggle arm 43 swings through an arc 46 about the pin 44 as a pivot; concurrently, the axis 36 of the cross bar 31 swings through an arc 47, the toggle crank 41 simultaneously rotating about the axis

36 until the two toggle members 22 assume a substantially co-linear or extended attitude. Slight continuing inertial motion in a leg-extending direction thereupon throws the toggle members 22 slightly beyond center, or beyond the co-linear attitude, so that as a limit stop flange 51 projecting transversely from the lower side of the toggle crank 41 is abutted by the adjacent portion of the toggle arm 43, the two toggle members are slightly cocked, or at a slight condition of angularity, as appears most clearly in Figure 5. With the toggle members in this beyond-center attitude, downward pressure on the table top serves to lock the toggle members even more securely. Laterally inward force on the leg 16 produces a comparable effect; and, since laterally outward force on the leg 16 is resisted by reason of the presence of the apron 9 and the bracket 38, the table legs are especially firm and secure against random blows and other forces. Owing, however, to the transverse limit stop 51 which projects laterally from the toggle arm 41 far enough to enable the user's fingers conveniently to grasp it or push against it, the toggle members can easily be urged off center in the opposite and leg-folding direction when it is desired to fold the legs.

The toggle members are swung from folded position to extended position by rotation of the cross bar 31, the cross bar 31 being rotated, in turn, by the turning effort exerted by a crank 56 mounted securely on the bar 31 adjacent one of the brackets 32. As shown most clearly in Figures 2 and 3, the crank 56 is, like the toggle member 41, mounted normal to the axis 36 of the bar 31, and is angularly displaced from the toggle member by only a slight amount, perhaps 15° or less.

The crank 56 is rotated by a link 57 pivotally mounted on the free end of the crank 56, as by a pin 58, the overlapping portions of the crank and link being held in place by a nut 59. Since the link 57 and the crank 56 not only move in a plane normal to the bar axis 36 but the link 57 moves laterally with respect to the crank 56, the nut is formed to assume a half-ball or knuckle joint configuration, as appears most obviously in Figure 1, the portion of the link 57 adjacent the nut being hollowed out or chamfered to conform with the knuckle.

The link 57 is itself moved by a rocker arm 61, the link being mounted on the rocker arm with considerable freedom of motion, i. e., both laterally and in rotation, owing to the provision of a knuckle-joint or beveled nut 62 and pin 63 (quite similar in construction to the nut 59) and shown most clearly in Figure 3. The rocker arm 61 is pivotally mounted as by a pin 66 centrally located on the member 11 and rotatable in a plane parallel to the table top.

The rocker arm 61, as shown in Figure 1, comprises an upper portion 71 as well as a lower portion 72, to which lower portion 72 the link 57 is connected. The upper portion 71 swings in an equal angular amount but in the opposite direction with respect to the lower portion 72. Since, as mentioned above, the mechanism on the right-hand side is substantially identical to that on the left-hand side, it is obvious that motion of the upper portion 71 of the rocker arm 61 is transmitted to the right hand pair of legs through a series of mechanisms and in a manner altogether comparable with those hereinbefore described.

The only significant variance between the right-hand and left-hand sides is the placement of the legs. Each of the legs of the left-hand leg, pair 16, as shown in Figure 1, is displaced upwardly from the corresponding or adjacent leg of the right-hand leg pair 76. While the displacement does not detract either from the sturdiness or the appearance of the table it does produce a slightly differing distance 81 between the leg and cross rail end at one end of the cross rail and longer distance 82 at the opposite end thereof. However, the distance 81 and the greater distance 82 are symmetrically disposed in diagonal fashion and the 75

adjacent arms of the brackets 27 and 28, respectively, are suitably dimensioned to accord with the two variant distances so as to give full limit-stop effect.

It can therefore be seen that all four of the table legs 5 are so interconnected and interlinked that movement of any one of the components is transmitted to all of the others. In operation, the user ordinarily places the table on one of its edges, for example, the bottom edge 86 shown in Figure 1, and with the bottom side shown facing away 10 from the user's body. A right-handed person would then ordinarily insert his hand between the upper leg (of the leg pair 16) and the table top and thrust the leg away from the table top. The thrust is transmitted to and down the cross rail 17 to the lower leg (of the leg pair 16) which 15 swings outwardly, and unfolds the toggle members 22, causing them to assume the over-center and locked position shown in Figures 3 and 5. Concurrently, as the toggle crank 41 is swung open the toggle crank 41 exerts a torsional or turning effort on the cross bar 31 which, in turn, 20 rotates the crank 56, pulls on the link 57 and rocks the rocker arm lower portion 72 to the position shown in outline in Figure 1. The upper rocker arm portion 71 is thereby swung through its corresponding arc, and its effort exerted through intermediate similar mechanism to cause 25 opening and locking of the other leg pair 76. While somewhat lengthy to describe, so slight is the friction between the parts and so advantageous are the leverages shown that with but slight effort even a child can swing all four table legs outwardly in a matter of a second or two.

30 In comparably convenient and effortless fashion, tripping of but one of the toggle members is sufficient to unlock all of the toggles, or diagonal brace members, permitting the user, by swinging inwardly only one of the table legs, to snap all of them shut or into folded position in the space 35 of a second or two.

It can therefore be seen that I have provided a card table which is not only sturdy, self-locking and well braced, but which also enables the user to open or close all legs in unison, with very little effort, yet with great rapidity.

40 What is claimed is:

A folding card table comprising a quadrilateral top, a plurality of pairs of legs, a pair of rails each connecting together the legs of one of said pairs, means for hinging said pairs of legs to the lower side of said top to swing 45 from a first position substantially parallel to said top to a second position substantially normal to said top, each of said legs being approximately as long as a side of said quadrilateral top and said legs of said pairs being interspersed when in said first position, a pair of bars 50 rotatably mounted on the lower side of said top and extending partially between said legs in said first position and said top, a plurality of pairs of toggle members, each pair of said toggle members being connected to one of said legs and to an adjacent end of one of said bars in a 55 location between said top and said one leg in said first position, a pair of crank arms, one crank arm of said pair being disposed on each of said bars and said crank arms being directed toward each other in said first position, a rocker arm extending approximately coplanar with and 60 entirely between the central ones of said interspersed legs in said first position, means for pivoting the central portion of said rocker arm to said top, and links connected to the opposite ends of said rocker arm and to respective ones of said crank arms.
